UNITED STATES PATENT OFFICE.

LEWIS M. PYLE, OF BRYN MAWR, PENNSYLVANIA, ASSIGNOR TO NILES-BEMENT-POND COMPANY, OF NEW YORK, N. Y., A CORPORATION OF NEW JERSEY.

METAL PLANER.

Application filed September 12, 1919. Serial No. 323,349.

To all whom it may concern:

Be it known that I, LEWIS M. PYLE, a citizen of the United States, residing at Bryn Mawr, in the county of Montgomery 5 and State of Pennsylvania, have invented certain new and useful Improvements in Metal Planers, of which the following is a specification.

This invention relates particularly to planers which are so large and heavy that certain of the adjustments thereof cannot be readily made by hand as has been customary. One of the adjustments that has heretofore been necessary to make by hand 10 is the swiveling of the tool carrying devices with respect to the saddles so as to provide for feeding at any desired angle. One object of the invention is to provide power operated means whereby the tool carrying 15 devices can be swiveled, these power operated means being under easy manual control.

Another object of the invention is to provide improved feed mechanism adapted to 20 be readily adjusted to provide coarse or fine feeds. As concerns this feature the invention is equally applicable to both large and small planers.

Other objects of the invention will appear 25 from the following specification and claims.

In the accompanying drawings there is shown the embodiment of the invention that is deemed preferable, but it is to be understood that various changes may be made 30 without departing from the spirit of the invention as set forth in the claims appended to this specification.

Of the drawings:

Fig. 1 is a fragmentary side view of a 35 planer embodying the invention.

Fig. 2 is a fragmentary front view.

Fig. 3 is a rear view of one of the saddles and associated devices.

Fig. 4 is a side view of the parts shown in 40 Fig. 3, this view being partly in section along the line 4—4.

Fig. 5 is a sectional view taken along the line 5—5 of Fig. 3.

Fig. 6 is a horizontal sectional view 45 through the feed mechanism along the line 6—6 of Fig. 7.

Fig. 7 is a side view of the feed mechanism.

Referring to the drawings, 1 represents the bed of a planer and 2 the work carrying 55 table which is longitudinally movable along the bed in the usual way. For reciprocating the table any suitable mechanism may be provided, but preferably there is an electric motor 3 which is directly connected 60 with the table and which is repeatedly reversed to drive the table forward and backward. For effecting the reversals of the motor 3 there is provided a pilot switch 4 which is adapted to be turned by a lever 5. 65 Dogs 6 and 7 are adjustably mounted on the table in position to engage the lever 5 and thus move the pilot switch and reverse the motor.

Positioned at the sides of the bed 1 are 70 uprights 8—8 and these are connected by an arch 9. Vertically adjustable along suitable guideways on the uprights is a cross rail 10. For effecting vertical adjustment of the cross rail there are provided screws 75 11—11 which are connected at their upper ends with a transverse shaft 12 by means of bevel gearing 13—13. Any suitable mechanism may be provided for rotating the shaft 12, but as illustrated use is made of an electric motor 14 mounted on the arch 9. The motor is connected with the shaft by means of suitable power transmitting mechanism including a manually operable clutch, these parts not being shown in detail, as they 80 constitute no part of the present invention.

Transversely movable along the cross rail 10 are two tool heads 15 and 16. For moving the tool heads and for controlling them there are provided three shafts 17, 18 and 90 19 which extend longitudinally of the cross rail and are rotatably mounted therein. The upper and lower shafts 17 and 18 are threaded and are provided with spline grooves and the central shaft 19 is provided 95 with a spline groove for purposes to be set forth.

If desired, additional tool heads may be mounted on the uprights for vertical movement in the usual way. Such side heads are 100 not illustrated, as it will be sufficient to illustrate and describe the invention as ap-

plied to the cross heads 15 and 16. The two heads 15 and 16 are similar and a description of one of them, as for instance 15, will suffice for both. As illustrated in a general way in Figs. 1 and 2 and in greater detail in Figs. 3, 4 and 5, each head includes a saddle 20 which engages guides formed on the cross rail.

Carried by the saddle 20 are tool carrying devices including a bracket 21 which is swiveled for movement about an axis extending in the direction of the table reciprocations. This bracket is held in position and guided by means of tongues 22-22 and 10 T-bolts 23-23 entering a circular T-slot 24 formed in the saddle. The swivel bracket 21 is provided with a guideway which is normally vertical and a slide 25 is lineally movable along this guideway. For moving 15 the slide there is provided a screw 26 which extends longitudinally of the slide and which is bodily movable therewith. The screw has threaded engagement with a nut 27. Means including bevel gearing 28 is 20 provided for manually turning the screw and it will be seen that when the screw is thus turned the slide will be moved longitudinally. Mounted on the slide 25 is a swivel plate 29 which is movable about a 25 pivot at 30. In order that the plate 29 may be conveniently turned, the upper part thereof is arcuate in form and is provided with worm teeth 31. Mounted on the slide 25 is a worm 32 which meshes with the 30 worm teeth 31. It will be seen that when the worm 32 is rotated the swivel plate will be turned about its horizontal axis of adjustment. Mounted on the swivel plate 29 is a clapper box 33 to which the cutting tool 35 may be secured in the usual manner, as for instance by means of bolts 34-34. The clapper box 33 is connected to the swivel plate 29 by means of a normally horizontal pivot pin 35. The clapper box with the tool 40 can move about this pin, thus permitting the tool to swing out of engagement with the work during the return stroke of the planer 45 table and to effect relief.

For moving the saddle along the cross rail either preliminarily for purposes of adjustment or during operation for the purpose of feeding, use is made of one of the before mentioned threaded shafts, in this case the shaft 17. Secured to the saddle at 50 the rear thereof is a nut 36 which projects into the longitudinal recess in the cross rail in which several shafts are located. This nut engages the shaft 17. It will be seen that when the shaft 17 is turned the saddle 55 and the parts carried thereby are moved longitudinally along the cross rail. For the other head 16 the construction is similar except that the shaft 18 is engaged so that rotation thereof will move the head.

The shafts 17 and 18 are ordinarily turned by power as will presently appear. However, in making preliminary adjustments it is difficult to exactly locate the saddles by means of the power devices. There is therefore preferably provided a mechanism located at each tool head whereby the head may be moved manually to a slight extent to effect final adjustment. As illustrated, this mechanism comprises a gear 36^a splined on the shaft 17, this gear meshing with a gear 36^b. This latter gear can be manually turned by means of a handle applied to a squared shaft 36^c.

For moving the slide 25 by power, use is made of the shaft 19. Splined on this shaft 80 is a bevel gear 37 which is adapted to mesh with a bevel gear 38, this second bevel gear being rotatably mounted in a bearing in the saddle 20 with its axis coincident with the axis of adjustment of the swivel bracket 85 21. Connected with the bevel gear 38 is a bevel gear 39 which meshes with a bevel gear 40 connected with the nut 27. It will be seen that when the shaft 19 is turned the nut 27 may also be turned with respect to 90 the screw, thus moving the slide 25 upward or downward. Inasmuch as the axis of the bevel gears 38 and 39 is coincident with the axis of adjustment of the swivel bracket 21, the bracket can be freely adjusted without 95 interfering with the power connection. In order that the same shaft 19 may serve for both heads, means is provided whereby the drive gear 37 for either head may be connected to or disconnected from the corresponding driven gear 38. As illustrated, the gear 37 is slidable with respect to the saddle under the control of a hand lever 42. It will be seen that by this mechanism the gear 37 can be brought into or out of mesh with the 100 gear 38, thus completing or breaking the power connection.

For operating the several shafts 17, 18 and 19 there is provided an improved mechanism which is mounted on one end of the cross rail. This mechanism preferably receives its power from an independent electric motor, which motor may be the aforesaid motor 14. As illustrated, there is provided a shaft 43 which extends transversely of the planer and which is directly geared to the motor 14. By means of bevel gearing at 44 this shaft is connected with a vertical shaft 45 adjacent one end of the cross rail. Splined on the shaft 45 and vertically movable with the cross rail, is a bevel gear 46 which meshes with a bevel gear 47 on a horizontal shaft 48 rotatably mounted in a casing 49 carried by the cross rail. This shaft 48 constitutes the initial power element on the cross rail.

For effecting intermittent feeding the following mechanism is provided. Secured to

the end of the shaft 48 is a crank arm 50 provided with an adjustable crank pin 51. A link 52 connects the crank pin 51 with one arm of a bell crank lever 53 mounted on a shaft 54. The other arm of the bell crank lever is provided with pawls 55 which are adapted to engage the teeth of a gear 56 rotatably mounted on the shaft 54. It will be seen that when the shaft 45 is rotated, the bell crank 53 is given an oscillatory movement and the bell crank by means of the pawls 55 serves to turn the gear 56 intermittently. The gear 56 constitutes an intermittently operating power feed element.

15 The gear 56 meshes with a gear 57 loosely mounted on a shaft 58 parallel with the shaft 54. Rotatably mounted on the shaft 54 is a gear 59, this gear being adjacent the gear 56 and connectible therewith. The gear 59 meshes with a gear 60 loosely mounted on the shaft 58. It will be observed that the gear 59 is smaller than the gear 56 and that the gear 60 is larger than the gear 57. Mounted on the shaft 58 between the gears 57 and 60 is a third gear 61. This gear is slidably mounted on the shaft and is movable under the control of a hand lever 62. Clutch teeth 63 are interposed between the gears 57 and 61 and similar clutch teeth 64 are interposed between the gears 60 and 61. It will be seen that, in accordance with the present invention, there are two differently speeded trains of power transmitting devices between the power element or gear 56 30 and the gear 61 and that the last said gear 61 can be turned at each actuation of the gear 56 through a relatively large angle by means of the clutch teeth 63 or through a relatively small angle by means of the clutch teeth 64.

40 At one end the gear 61 meshes with a gear 65 mounted on a shaft 66, this shaft also carrying a gear 67. Rotatably mounted on a shaft 68 are two similar gears 69 and 70 which mesh respectively with the aforesaid gear 67 and the aforesaid gear 61. The gear 69 meshes with gears 71, 72 and 73 loosely mounted respectively on the shafts 17, 19 and 18. The other gear 70 meshes with similar gears 74, 75 and 76 also mounted 45 respectively on the said shafts 17, 19 and 18. From a study of the gearing which has been described, it will be seen that the two gears 69 and 70 are rotated in opposite directions and that the sets of gears 71, 72 and 73 and 50 74, 75 and 76 will also be rotated in opposite directions. Mounted on each of the shafts 17, 19 and 18 is a clutch element 77 adapted to be moved by a hand lever 78. Each clutch element is splined on its shaft, as for instance

55 60 as illustrated in Fig. 6, and it can be engaged either with the gear 71 or with the gear 74, thus connecting the shaft for rotation in either direction as desired.

When the mechanism is to be used for

feeding, the shaft 45 is given one complete revolution at the end of each table reciprocation, this being preferably brought about by operating the motor to a definite extent by suitable electrical controlling devices operated by the planer table. At each such revolution of the shaft 45 the gear 56 is rotated through a definite angle which angle can be varied by changing the adjustment of the crank pin 51. The gears 69 and 70 are moved in opposite directions through definite angles corresponding to the angle of movement of the gear 56, the extent of movement being adjustable by moving the gear 61 to engage and disengage the clutch teeth 63 and 64. Thus the gears 71, 72 and 73 are turned in one direction and the gears 74, 75 and 76 are turned in the other direction. By properly adjusting the several clutch elements 77, the several shafts 17, 19 and 18 can be turned in either direction as desired, thus effecting transverse feeding of either head in either direction or effecting vertical feeding of either or both of the tools in either direction.

For continuously moving the tool heads or the tools to effect preliminary adjustments the following mechanism is provided. Secured to the aforesaid shaft 48 is a gear 79 which meshes with an idler gear 80 which idler gear in turn meshes with a gear 81 loosely mounted on the aforesaid shaft 54 and constituting a driving element for use during preliminary adjustments. It will be seen that when the shaft 45 is continuously rotated, the gear 81 is also continuously rotated. It will be observed that the gear 59 is located between the gears 56 and 81. Clutch teeth 82 are interposed between the gears 56 and 59 and similar clutch teeth 83 are interposed between gears 81 and 59. The gear 59 can be moved longitudinally by means of a hand lever 84 to engage the teeth at 82 or the teeth at 83 as desired. Thus the gear 59 can be caused to rotate intermittently with the gear 56 or continuously with the gear 81.

When the mechanism is to be used for the preliminary adjustment of the tool heads, the clutch teeth at 83 and also those at 64 are engaged and the shaft 45 is operated continuously. The several gears 71, 72 and 73 and 74, 75 and 76 are then rotated continuously but in opposite directions. By properly adjusting the clutch elements 77 any of the shafts 17, 19 and 18 can be turned in either direction to effect the desired adjustments of the tool heads or of the tools.

In accordance with the present invention, there is provided power mechanism whereby either swivel bracket 21 may be turned with respect to the saddle 20. The power mechanism for swiveling the bracket is preferably operated by the power feed mecha-

nism which serves to move the saddle and the tool carrying devices in the way already described. As illustrated, use is made of the before mentioned shaft 19. Mounted on this shaft is a worm 85 which meshes with a worm wheel 86 mounted on the saddle and rotatable about an axis parallel with the axis of adjustment of the swivel bracket. Connected with the worm wheel 86 is a pinion 87. This pinion 87 meshes with gear teeth 88 formed on the bracket 21. It will be seen that when the worm wheel 85 is rotated by means of the shaft 19, power will be transmitted to rotate the gear 87 and thus turn the bracket 21 and the parts carried thereby. In order that the movement of the swivel bracket may be manually controllable, there is provided a clutch 89 between the shaft 19 and the worm 85. Preferably use is made of the before mentioned slidable bevel gear 87, clutch teeth being formed thereon at 89 which are adapted to be moved into or out of mesh by the before mentioned lever 42. Thus the same hand lever serves either to move the gear 87 into mesh with the gear 88 for the vertical movement of the slide 25 or serves to engage the clutch teeth at 89 for the swiveling of the tool carrying devices.

30 It is difficult to secure exactly the desired adjustment by means of the power mechanism and there is therefore provided manually operable means whereby final adjustment may be effected. For this purpose 35 there is provided a gear 90 connected with the worm 85, this gear 90 meshing with a gear 91. Gear 91 may be turned manually by means of a handle applied to a squared shaft 92.

40 What I claim is:

1. In a planer, the combination with the bed, the reciprocating table and the saddle movable transversely of the table reciprocations, of tool carrying devices swiveled on the saddle for movement about a horizontal axis extending in the direction of the table reciprocations, and power mechanism including a shaft extending parallel with the line of movement of the saddle for swiveling the tool carrying devices.

2. In a planer, the combination with a bed, the reciprocating table and the saddle movable transversely of the table reciprocations, of tool carrying devices swiveled on the saddle for movement about a horizontal axis extending in the direction of the table reciprocations, power feed mechanism for moving the saddle and tool carrying devices, and mechanism operable by the feed mechanism for swiveling the tool carrying devices.

3. In a planer, the combination with the bed, the reciprocating table and the saddle movable transversely of the table reciprocations, of tool carrying devices swiveled on the saddle for movement about a horizontal

axis extending in the direction of the table reciprocations, a feed motor for moving the saddle and tool carrying devices, and mechanism operable by the feed motor for swiveling the tool carrying devices.

4. In a planer, the combination with the bed, the reciprocating table and the transverse cross rail, of a saddle movable along the cross rail, tool carrying devices swiveled on the saddle for movement about a horizontal axis perpendicular to the cross rail, and power mechanism including a shaft extending parallel of the cross rail for swiveling the tool carrying devices.

5. In a planer, the combination with the bed, the reciprocating table and the transverse cross rail, of a saddle movable along the cross rail, tool carrying devices swiveled on the saddle for movement about a horizontal axis perpendicular to the cross rail, power mechanism for swiveling the tool carrying devices, and a manually operable clutch on the saddle for controlling the power mechanism.

6. In a planer, the combination with the bed, the reciprocating table and the transverse cross rail, of a saddle movable along the cross rail, tool carrying devices swiveled on the saddle for movement about a horizontal axis perpendicular to the cross rail, power feed mechanism for moving the saddle and tool carrying devices along the cross rail, and mechanism operable by the feed mechanism for swiveling the tool carrying devices.

7. In a planer, the combination with a bed, the reciprocating table and the transverse cross rail, of a saddle movable along the cross rail, tool carrying devices swiveled on the saddle for movement about a horizontal axis perpendicular to the cross rail, the said devices including means permitting lineal movement of the tool with respect to the saddle, a feed shaft extending longitudinally of the rail for moving the tool lineally as aforesaid, and mechanism operable by the said shaft for swiveling the tool carrying devices.

8. In a planer, the combination with the bed, the reciprocating table and the transverse cross rail, of a saddle movable along the cross rail, tool carrying devices swiveled on the saddle for movement about a horizontal axis perpendicular to the cross rail, the said devices including means permitting lineal movement of the tool with respect to the saddle, a feed shaft extending longitudinally of the rail, means adapted to be operated from the said feed shaft for moving the tool lineally as aforesaid, means adapted to be operated from the said feed shaft for swiveling the tool carrying devices, and means including a single operating handle for operatively engaging either of the last two mentioned means with the feed shaft.

9. In a planer, the combination with the

bed, the reciprocating table and the transverse cross rail, of a saddle movable along the cross rail, tool carrying devices swiveled on the saddle for movement about a horizontal axis perpendicular to the cross rail, the said devices including means permitting lineal movement of the tool with respect to the saddle, a feed shaft extending longitudinally of the rail for moving the tool lineally as aforesaid, a worm carried by the said shaft, a worm wheel meshing with the worm, and gearing operated by the worm wheel for swiveling the tool carrying devices.

10. In a planer, the combination with the bed, the reciprocating table and the transverse cross rail, of a saddle movable along the cross rail, tool carrying devices swiveled on the saddle for movement about a horizontal axis perpendicular to the cross rail, the said devices including a tool slide lineally movable with respect to the saddle, a feed shaft extending longitudinally of the rail, means including a bevel gear carried by the shaft for moving the tool slide lineally as aforesaid, a worm also carried by the said shaft, a worm wheel meshing with the worm, and gearing operated by the worm wheel for swiveling the tool carrying devices.

11. In a planer, the combination with the bed, the reciprocating table and the transverse cross rail, of a saddle movable along the cross rail, tool carrying devices swiveled on the saddle for movement about a horizontal axis perpendicular to the cross rail, the said devices including a tool slide lineally movable with respect to the saddle, a feed shaft extending longitudinally of the rail, means including a bevel gear carried by the shaft for moving the tool slide lineally as aforesaid, a worm also carried by the said shaft, a worm wheel meshing with the worm, gearing operated by the worm wheel for swiveling the tool carrying devices, and a single lever for controlling both the aforesaid bevel gear means for moving the slide and the said worm and wheel for effecting swiveling.

12. In a planer, the combination with the bed, the reciprocating table and the transverse cross rail, of a saddle movable along the cross rail, tool carrying devices swiveled on the saddle for movement about a horizontal axis perpendicular to the cross rail, the said devices including means permitting lineal movement of the tool with respect to the saddle, a feed shaft extending longitudinally of the rail for moving the tool lineally, mechanism operable by the said shaft for swiveling the tool carrying devices, and means operable manually independently of the said shaft for also effecting swiveling.

13. In a planer, the combination with the bed, the reciprocating table, the transverse cross rail and the tool head movable along the rail, of a feed screw extending along the

rail and engaging the tool head, an intermittently turning power feed element, and two optionally usable differently speeded trains of power transmitting devices between the said power element and said screw for effecting coarse or fine feed as desired. 70

14. In a planer, the combination with the bed, the reciprocating table, the transverse cross rail and the tool head movable along the rail, of a feed screw extending along the rail and engaging the tool head, an intermittently turning power feed element, two optionally usable differently speeded trains of power transmitting devices comprising two sets of gearing between the said power element and said screw for effecting coarse or fine feed as desired, and means for operatively engaging either set of gearing. 75

15. In a planer, the combination with the bed, the reciprocating table, the transverse cross rail and the tool head movable along the rail, of a feed screw extending along the rail and engaging the tool head, two gears rotatably mounted on the feed screw, mechanism for driving the said gears in opposite directions, means for clutching either gear to the screw to effect feeding in either direction as desired, an intermittently turning power feed element, and two optionally usable differently speeded trains of power transmitting devices between the said power element and the said gear driving mechanism for effecting coarse or fine feed as desired. 90

16. In a planer, the combination with the bed, the reciprocating table, the transverse cross rail and the tool head movable along the rail, of a feed screw extending along the rail and engaging the tool head, an intermittently turning power feed element carried by the cross rail, and two optionally usable differently speeded trains of power transmitting devices on the cross rail between the said power element and the said screw for effecting coarse or fine feed as desired. 100 105 110

17. In a planer, the combination with the bed, the reciprocating table, the transverse cross rail and the tool head movable along the rail, of a feed screw extending along the rail and engaging the tool head, an intermittently turning power feed element carried by the cross rail, two gears connected with the feed element to be turned thereby to different extents, a third gear adapted to be driven by either of the said gears, and mechanism connecting the said third gear with the screw. 115 120

18. In a planer, the combination with the bed, the reciprocating table, the transverse cross rail and the tool head movable along the rail, of a feed screw extending along the rail and engaging the tool head, an initial power element on the cross rail adapted to be turned continuously, a power feed ele- 125 130

5   element adapted to be intermittently operated means for disconnecting the power feed ele-
      by the said initial power element, a driving ment from the said trains of devices and 10
      element adapted to be continuously operated connecting the said driving element with
      by the said initial power element, two op- one of the said trains for effecting prelimi-
      tionally usable differently speeded trains of nary adjustments.
      power transmitting devices between the said In testimony whereof, I hereto affix my
      power feed element and the said screw for signature.

LEWIS M. PYLE.
